PAVING JOINT

Frank H. Scrivner and Allan L. Chollar, Austin, Tex.

Application January 5, 1951, Serial No. 204,536

2 Claims. (Cl. 94—17)

This invention pertains to pavements and to paving joints and more particularly to contraction joints for concrete roads and methods of making same.

According to older practice, road pavements were built in slabs and periodically along the road at distances several slabs apart fairly large gaps were left between adjoining slabs, these gaps being filled with wood or other material and known as expansion joints. The purpose of such expansion joints is to leave space for expansion of the concrete in hot weather, thereby avoiding high compressive stresses with resultant failure of the concrete by buckling, cracking, spalling or crumbling. In cold weather each individual slab can contract separately and the joints between them are known as contraction joints. Contraction joints are desirable to prevent random cracks in the paving which might otherwise be produced due to contraction in cold weather, concrete being markedly weaker in tension than in compression. Both types of joints may allow the paving slabs to warp when exposed to different temperature on top and bottom. Various means are used to seal the expansion and contraction joints and to interlock the adjoining slabs against vertical misalignment.

It has been found that in cold weather when the contraction joints are open they fill up with debris and on re-expansion of the concrete in the summer the contraction joints remain open and the paving slabs shift position bodily so that their mid-points, relative to which their ends move in expansion and contraction, move closer to the expansion joints. In other words, the widths of the expansion and contraction joints tend to equalize. This process is cumulative, and within a few years the expansion joints sometimes close to the full extent permitted by the filler, and as a result such pavements have been observed to suffer equal or greater damage from high compressive stress than probably would have been the case had no expansion space been provided in the first place. In addition, contraction joints depending on "aggregate interlock" for load transfer (to be described below) lose this interlock and eventually suffer vertical misalignment, thus increasing the impact of traffic at the joint and leading to further damage.

Because of these phenomena, more than one-third of the State Highway Departments of the United States now build concrete highways without provision for expansion except at bridge ends and similar special locations.

Transverse paving joints may be classified into two groups. In one group are those joints provided with various types of metal members, e. g. dowel pins, bridging the joint to provide load transfer. These joints require extensive forms to be laid before the concrete is poured. In the second group the "joint" is a mere crack in the paving and the interlock is provided by the irregular surface of the concrete at the crack. Such interlock is called "aggregate" interlock and the cracks may be induced at regular intervals by forming grooves in the concrete surface about a third of the way down through the pavement, such grooves being known as dummy joints.

2

The grooves are formed in the wet concrete, which is laid as a monolithic slab, and the monolithic slab is supposed to break into several slabs along the grooves when the concrete shrinks during setting or immediately thereafter when the paving is first loaded with traffic. However, oftentimes the concrete does not crack at each groove and there are left long unbroken slabs so that in cold weather the joints at the places where the concrete does crack open up very wide with resultant leakage and loss of interlock.

According to the present invention a joint is provided combining the advantages of the known kinds of joints with additional advantages of its own while omitting the disadvantages.

It is an object of the invention to provide a pavement which will with certainty have joints at regular predetermined intervals.

It is another object of the invention to provide a joint which is interlocked over the whole vertical depth.

It is another object of the invention to provide a joint which is interlocked continuously over the whole face of the joint.

It is a further object of the invention to provide a joint whose interlocking parts will not break off easily.

It is a further object of the invention to provide a joint with tapering interlocking portions which will wedge the adjoining concrete slabs into proper vertical alignment following wide separation instead of crushing the misaligned abutting protruberances.

It is a further object of the invention to provide a joint with interlocking portions that will maintain proper vertical alignment at all times during normal motion of separation and return.

It is still another object of the invention to provide a joint that will be substantially sealed in all positions of expansion and contraction regardless of whether or not any auxiliary rubber or asphalt sealing compound is used to fill the joint, thereby preventing water from leaking into the subgrade and being pumped out again as a load passes over the joint, both of which tend to wash away the subgrade, and also preventing collection of debris in the joint which might prevent its reclosure.

It is still another object of the invention to provide a joint that will at all times maintain proper vertical alignment so as to prevent pumping and eliminate bumps and broken edges at high places.

It is still another object of the invention to provide a joint that will effectively transmit load from one slab to the next, regardless of the temperature, thereby avoiding cracks due to cantilever loading of the slab ends.

Yet another object of the invention is to provide a joint that is easy to install, that can be vibrated into place, that has wide tolerances as to its position in the concrete, that is rugged, that will withstand the considerable abuse of normal road construction operations, that will not interfere with pouring, that will leave a clean subgrade over which rolling equipment can easily travel.

It is another object of the invention to provide a joint that will be very low in cost.

Other objects and advantages of the invention will become apparent as the description thereof proceeds.

Reference will now be made to the accompanying drawings illustrating a preferred embodiment of the invention wherein:

Figure 1 is an isometric view of a portion of a concrete road pavement just after it has been poured and showing the manner of formation of a joint therein according to the invention;

Figure 2 is an elevational sectional view taken along line 2—2 of Figure 1 and shows a joint embodying the invention.

Figure 3 is an isometric view of a portion of a piece

of joining hardware made according to the invention; and

Figure 4 is a detail of a small portion of a very widely opened joint enlarged three or four times over preferred actual size, and illustrates in particular the very small size of vertical clearances between interlocking elements in spite of horizontal opening of the joint which is some eight times wider than normal maximum opening.

Referring to Figure 1, there is shown road pavement 10 below the surface of which is set a form 11. The form is shown best in Figures 2 and 3 and comprises a piece of sheet steel, preferably not less than 28 gage (.0135 in.) in thickness and shaped by pressing, rolling, or other suitable manner to provide a rippled or wavy surface having parallel hills and valleys giving a sinuous or S shaped cross section. Preferably the parallel half waves 12 are each half cylinders formed on a half inch radius and alternately concavely and convexly disposed when viewed from one side of the form or the other. Along the top edge of the form there is a straight flat surface 13 lying in a plane that is midway between the crests and valleys of the half waves 12.

The plane of the flat 13 may be considered as a central reference plane of the form, containing the axes of the half-cylinders which constitute the half waves 12, and also the lines or straight line elements, along which these half-cylinders are tangentially joined. Moreover, when the reference plane is vertical, the surface of the corrugated form, at the line of tangency between two half-cylinder waves, is horizontal. As is apparent from Figure 4, a tangent 16 to the corrugated surface, tangent at the juncture of two waves 15, is horizontal. It is of some significance that the half waves be joined along lines at which the surface of the form is substantially horizontal.

Phrased another way with Figure 3 in mind, it may be said that the corrugated surface comprises an infinite number of straight line elements, all of which are parallel to each other and substantially horizontal. The corrugations themselves, being formed of these straight line elements, are horizontally disposed. Adjacent corrugations are joined by a horizontal element lying in the central reference plane and the corrugated surface, at its intersection with the central reference plane, is horizontal. That is, the semi-cylindrical sections, at their intersections with the central reference plane as at 15 in Figure 4, are tangent to horizontal planes such as that indicated by the dash line 16 in Figure 4.

Immediately after the concrete has been poured on the subgrade as shown in Figure 1, the forms 11 are pushed into the concrete from above, a vibrator being used to assist in the operation. The form is pushed well below the top of the concrete, lying about a quarter to a half inch below the top at the edges of the pavement and a greater distance in the middle of the central crowned portion.

The form is of such height as to extend within an inch of the bottom of the pavement.

It is permissible for the form to extend all the way from the top to the bottom but that would necessitate cutting the form with an arcuate top exactly fitting the road contour of crowned roads and if the form were not forced all the way to the bottom it would extend above the surface of the road and cut the tires of vehicles passing over the road. Since a satisfactory joint is achieved with the form extending only close to the bottom and top of the paving such construction is much to be preferred for it gives considerable tolerance in placing the forms. More important still, there is a saving in cost of the form and in labor time in installing it. Burying the form in the concrete also insures that it is not exposed by slight spalling of the pavement surface adjacent the joint and provides a narrower space between adjoining pavement sections at the surface.

The form is coated on one or both sides with paint or other material so that the form does not adhere to the concrete on both sides. This insures that the concrete

will break into separate slabs along the forms when it shrinks during setting. The flat vertical tongue 13 causes the concrete above the form to crack in a vertical plane instead of slanting off leaving a wafer thin edge. If desired a similar tongue 14 may be provided at the bottom of the form, but the shape of the crack at the bottom is not as important since it is not exposed to traffic and is supported on all sides.

The forms are placed at intervals of ten to fifteen feet for the usual road pavement. This is shorter than the length of the slabs into which a monolithic concrete pavement would naturally break up due to subgrade friction resisting the contraction and expansion of the concrete and building up stresses greater than the strength of the paving.

In use the joints permit temperature contraction of the undivided short slabs of pavement without further cracking. To the extent that gaps are left due to shrinkage during setting, there is also provided some space for expansion. The nearly horizontal upper and lower sides of each semicylindrical corrugation on the faces of adjoining slabs maintain almost perfect vertical alignment despite expansion or contraction, allowing a vertical misalignment of less than two one-hundredths of an inch upon an extreme separation of one-tenth of an inch.

In order to illustrate the very small vertical clearance in comparison to horizontal opening of the joint, it was necessary in Figure 4 to draw a horizontal opening (designated by the arrow 17) which is some eight times the normal maximum openings in pavements without expansion joints, just to get a vertical clearance 18 large enough to be seen in the drawing. On the other hand, the mating gear tooth like protrusions from the slab ends or faces part slightly throughout the entire face with ever so slight a horizontal opening, thus permitting a free opening of the joint without placing tensile stresses on the protrusions.

Following even such an extreme separation as illustrated in Figure 4, and during subsequent periods of higher temperature, the joint will close with no danger of jamming, since the slope of the element at a horizontal distance of one-tenth of an inch from its center is less than twelve degrees (angular measurement) from the horizontal. As the joint closes the elements act as wedges to re-align the adjoining sections. The rounded edges prevent crumbling or cracking during this process. There are no stress concentrations such as would occur with trapezoidal or square tooth forms.

Another advantage of the sinuous shape of the form lies in the fact that if it is placed in position as much as 15 degrees away from vertical it will still function satisfactorily. A further advantage of the sinuous cross section is that it facilitates vibrating the forms into place while assuring that the concrete fills in completely on both sides of the form and packs tight.

The forms are made of steel or like material having a high compressive strength so that the shaped part of the joint as well as that portion above and below the form will share load equally, both compressive stresses upon expansion and compound stresses during passage of a vehicle over the joint.

Since the joint maintains interlock despite relatively large horizontal separation of adjoining slabs, the ends of the slabs remain supported and do not crack off or bend down and pump water in and out of the joint as traffic passes over, nor jar the vehicles due to vertical misalignment. Also the joint is sealed along the area of contact between each adjoining pair of elements and this too prevents pumping as well as keeps surface water from entering and dirt and debris from blocking the joint.

A more full understanding of why the joint of this invention is so greatly superior to other joints (as has been proved by literally hundreds of miles of highway joints without a single failure) can be obtained only with an understanding of the kinds of movements which occur

at joint. First, there is a horizontal opening and closing of the joints resulting from seasonal expansion and contraction in summer and winter.

Second, there is a movement in the nature of oscillating gears at each joint, which movement occurs almost daily. Each day when the sun comes up, the tops of the slabs heat sooner than the bottoms, with the result that the slab ends, i. e., the joints, move downward relative to the slab centers. Later in the day, the upper side of the slab cools faster than the lower side, and the slab ends move upward with respect to the centers of the slabs. In the morning the bottom of the joint opens while the top remains closed, and in the evening the top opens while the bottom remains closed or closes. Thus there is a small oscillative rotation of the slab ends about the slab centers, and this rotation, though small in amplitude, is of sufficient size to set up great stresses at joints which are not completely flexible to permit this rotation freely. The tooth form of this invention does permit this complete freedom of rotation, whether the joint is horizontally open or closed, without sacrificing the load transfer and other characteristics of the joint.

Third, as appears from the above, the joint must not permit appreciable vertical movement of slab ends before load transfer is effected, regardless of the amount of opening or warping that may be present at any given time. To do so sets up great tension stresses in the top of the slab a short distance from the joint, causing eventual failure. Failure to effect full load transfer without appreciable vertical movement also produces other deleterious effects not necessary to discuss here.

The requirements of structure to allow for the various movements and for efficient load transfer are such as to make the preferable form one having semi-cylindrical corrugation sections, pairs of semi-cylindrical sections being tangentially joined along lines where the surface is horizontal. The efficiency of the joint is not affected by some of the sections being semicylinders of somewhat larger diameter than others, in which event the peaks may not all be exactly equidistant on opposite sides of the "reference plane" of the form. Also, a form in which the peaks of the half-waves have been cut off or mashed in somewhat, but without making sharp edges, is obviously the equivalent, for purposes of this invention, of the preferred form having all one inch diameter half-cylinder corrugations.

From the foregoing description it is believed that it will be apparent how the joint according to the invention achieves the stated objects of the inventor. However, while a preferred embodiment of the invention has been shown and described, many modifications thereof can be made by one skilled in the art without departing from the spirit of the invention and it is desired to protect by Letters Patent all forms of the invention falling within the scope of the following claims.

We claim:

1. A concrete pavement divided into a plurality of slabs by means of sheet members; said sheet members being corrugated into a predetermined wave form with alternate half waves extending substantially equal distances

5 on each side of a central reference plane; said sheet members being disposed in said concrete with said plane vertical and with the corrugations horizontally disposed; each of said corrugation half waves being a semi-cylindrical section; said semi-cylindrical section being tangentially joined along lines located in said central reference plane; each semi-cylindrical section, at its intersection with the central reference plane, being tangent to a horizontal plane; said corrugated half waves being filled with 10 dense concrete including aggregate; said sheet defining the form of the abutting faces of two adjacent slabs of pavement to be in the nature of cooperating gear teeth which may freely move horizontally to opened and closed positions with seasonal contraction and expansion of the slabs while continually interlocking sufficiently to effectively transfer load from one slab to the adjoining slab; said gear teeth form of abutting faces of the slabs also cooperating to permit the top and bottom of the joint between two adjacent slabs to alternately open and close with thermal warping of the slabs without introducing substantial stresses into said teeth.

2. A concrete pavement divided into a plurality of slabs by means of sheet members; said sheet members being corrugated into a predetermined wave form with alternate half waves extending on each side of a reference plane; said sheet members being disposed in said concrete with said plane substantially vertical and with said corrugations substantially horizontally disposed; each of said corrugation half waves being a semi-cylindrical section; said semi-cylindrical section being tangentially joined along lines located in said reference plane; each semi-cylindrical section, at its intersection with said reference plane, being substantially tangent to a horizontal plane; said corrugation half waves being filled with dense concrete including aggregate; said sheet defining the form of the abutting faces of two adjacent slabs of pavement to be in the nature of cooperating gear teeth which may freely move horizontally to opened and closed positions with seasonal contraction and expansion of the slabs while continually interlocking sufficiently to transfer load from one slab to the adjoining slab; said gear teeth form of abutting faces of the slabs also cooperating to permit the top and bottom of the joint between two adjacent slabs to alternately open and close with thermal warping of the slabs without introducing substantial stresses into said teeth.
